EBEN F. OLIVER, OF JERSEY CITY, NEW JERSEY, ASSIGNEE, BY DIRECT AND MESNE ASSIGNMENTS, TO KORECTOLITE COMPANY, INC., OF NEW YORK, N. Y., A CORPORATION OF NEW YORK.

LIGHTING FIXTURE AND PROCESS FOR PRODUCING SAME.

Application filed February 27, 1920. Serial No. 361,382.

To all whom it may concern:

Be it known that I, EBEN F. OLIVER, a citizen of the United States, and a resident of Jersey City, county of Hudson, and State 5 of New Jersey, have invented new and useful Lighting Fixtures and Processes for Producing Same, of which the following is a specification.

The present invention relates generally to 10 lighting fixtures and more particularly to means whereby so-called daylight effects may be produced by use of light from incandescent lamps.

The field for the use of artificial daylight 15 is an important one and comprises the illumination of show-windows, automobile head lights and color-matching devices and of such places in which accurate machine work, printing, engraving, etc., is done and 20 where actual daylight effect without glare is desirable.

To produce daylight effects by the use of light from an incandescent lamp, it is necessary to eliminate some rays of objectionable color and this may be accomplished by 25 causing the light rays to pass through a complementary color screen. It has been attempted to accomplish this by making the bulb of an incandescent lamp of glass colored 30 before the bulb is blown by introducing into the batch coloring matter of a suitable color, say blue. Since, however, it is impossible to obtain coloring material of absolutely uniform value and since the coloring matter 35 has to be introduced in the dry batch and cannot be changed after melting begins, it has been found impossible to control the color of the glass scientifically or accurately. Also when blowing the bulb the operator 40 cannot take an exact amount of glass on the pipe, and the result is that the bulb so blown is thicker or thinner in different parts, and this tends to seriously alter its color value.

It has also been found that the color value 45 of the light-corrective medium is disastrously affected when brought, as it is when the bulb is used as such medium, into direct contact with the particles thrown off by the filament when in a state of incandescence.

50 These particles adhere to the walls of the bulb and cause discoloration of the glass which not only reduces the candle power of the lamp but changes the color of the transmitted light thereby destroying its useful

ness as a light-corrective medium. In nitrogen or other gas-filled lamps, the particles thrown off by the filament, being lighter in weight than the gas, should, theoretically, rise to the neck of the lamp and there be deposited provided the lamp is in a vertical 55 position with the neck uppermost. The present day use of these lamps is, however, for such varied purposes, some of which require a high degree of concentration of light at a given point and others diffusion of the light, 60 that it is impossible to always dispose the lamp so that it will be in a vertical position and, when the lamp is not in that position, obviously, the particles will nevertheless 65 rise and be deposited on that part of the lamp which is uppermost. The deterioration caused by this so-called "bombarding" of the filament previously described sets in as soon as the lamp is lighted and progresses rapidly. A further disadvantage in the use 70 of such blue bulbs is that when the lamp is used in connection with a reflector, the value of the light transmitted to the reflector is very slight and the loss in efficiency correspondingly great. 75

It has been also attempted to place a plate of glass painted blue or blue and green in the mouth of a reflector to thereby obtain 80 daylight effect. It has been found that this is also adversely affected by conditions of 85 temperature and by the element of time and that it is difficult to obtain a uniform depth of color.

It will be seen from the above that in the 90 art as heretofore practiced there have been difficulties attending the manufacture and use of devices for producing daylight effects and that it has not been possible to obtain the same effects at different times.

The main object of this invention therefore 95 is to produce means whereby the light of an incandescent lamp, whether of the vacuum or gas-filled type, may be "corrected" or modified with such degree of uniformity as is necessary to obtain approximate daylight 100 values and in such manner as to protect the light-corrective medium from the bombardment of the filament.

I have ascertained by experiments that the 105 color value of the light-corrective medium may be so controlled as to admit of the production, at will, of the same daylight effects and I accomplish this by making the light

corrective medium of glass, such as that used for window panes, the surface of which is subjected to a sand blast of quartz-sand (that is irregular shaped particles of sand) 5 so as to produce irregular interstices therein, then in filling said interstices with a coloring agent. The surface thus produced is then covered with an agent that seals the coloring matter in the interstices and tends 10 to restore the translucency of the glass. Greater efficiency may be obtained in this manner for the lamp when used in connection with a reflector since the full value of the light from the bulb will be received by 15 the reflector and thereafter transmitted through the light corrective medium.

The requisite intensity of color of the light-corrective medium will be determined by the characteristics of the light given by 20 the lamp in connection with which the light-corrective medium is to be used. Should it be desired to color only one side of the glass, the other side may be coated with an acid-resisting material in a manner well known.

25 In the accompanying drawings:

Fig. 1 is a sectional view of a lighting fixture showing one form of the invention:

Fig. 2 is a sectional view of another lighting fixture having a reflector showing another embodiment of the invention.

Fig. 3 is a detail view showing the light corrective medium in cross section after having been subjected to the action of the sandblast and with the irregular interstices 35 indicated.

Fig. 4 is a view similar to Fig. 3 with the coloring matter added.

Fig. 5 is a view similar to Fig. 4 with the sealing varnish applied.

40 1 indicates an incandescent lamp, such as a tungsten filament lamp, of the vacuum type, known commercially as a Mazda C lamp, having a translucent bulb as shown; or, it may be an incandescent lamp of the 45 character generally designated as nitrogen or other gas-filled lamp. 2 is a corrective-light medium surrounding the bulb and consisting of a piece of translucent glass suitably shaped and colored. In Fig. 2 the bulb 50 1 is shown as being contained within a reflector 3 having an open mouth 4 in which is placed the light corrective medium 2.

The reflector may be of a trough-like character or of any other suitable type, such, 55 for instance, as is commercially known as an X-ray reflector; and the light corrective medium may be held in place in the mouth of such reflector by clips 5, or otherwise.

In Figs. 3, 4 and 5, I have shown the steps 60 used in preparing the light corrective medium. The action of sharp and irregular quartz-sand against the surface of the glass is shown in Fig. 3 where irregular interstices 6 are indicated. Care should be taken 65 in sandblasting the surface that no streaked

or even effect is produced. A coloring agent 7 is then introduced into the irregular interstices, as shown in Fig. 4, and "pounced" or rubbed in well. Finally, a translucent varnish 8 is applied which seals the coloring agent in place and by producing a substantially flush surface tends to restore the translucency of the glass. This varnish is then baked to harden it. It will be understood that by this method the color value may be 75 accurately controlled, since the amount of color may be increased or decreased to suit varying conditions.

I claim:

1. The process of producing a light-corrective medium which consists in producing irregular interstices throughout the surface of a sheet of translucent glass, and then in filling said interstices with a coloring agent 80 to uniformly color the medium.

2. The process of producing a light-corrective medium which consists in producing irregular interstices throughout the surface of a sheet of translucent glass, then in filling said interstices with a coloring agent 85 to uniformly color the medium, and then in covering the surface so produced with an agent that seals the coloring matter in the interstices and tends to restore the translucency of the glass.

3. The process of producing a light-corrective medium which consists in producing irregular interstices throughout the surface of a sheet of translucent glass, then in filling said interstices with a coloring agent to 95 uniformly color the medium, then in applying a translucent varnish to the colored surface, and then in applying heat to the glass to harden the varnish.

4. A lighting fixture comprising: an incandescent lamp having a translucent bulb, and a light corrective medium extraneous of said bulb and associated therewith consisting of a glass member having irregular interstices throughout its surface, said interstices being filled with a coloring agent of such value as to uniformly color the medium to thereby correct the light of the incandescent lamp to approximate daylight value.

5. A lighting fixture comprising: an open mouth reflector, an incandescent lamp having a translucent bulb within said reflector, and a light corrective medium, closing the mouth of said reflector, consisting of a glass member having irregular interstices throughout its surface, said interstices being filled with a coloring agent of such value as to uniformly color the medium to thereby correct the light of the incandescent lamp to 115 approximate daylight value.

Signed at New York city, in the county of New York and State of New York, this 26th day of February, 1920.

EBEN F. OLIVER.
